NAIL PULLER

Carl A. Husa, Oakland, Calif.

Application June 27, 1952, Serial No. 296,029

1 Claim. (Cl. 254—24)

This invention relates to hand tools, and more particularly, has reference to a tool specifically adapted to facilitate the extraction of nails and like objects from surfaces in which they are deeply embedded.

In most instances, a claw hammer or similar tool is entirely sufficient for the purpose of pulling nails. However, on some occasions, a claw hammer is inadequate to accomplish the desired extraction of the nail, due to the fact that the nail is embedded too deeply within the wood.

The present invention is intended specifically for extracting nails which resist pulling by a conventional claw hammer or like tool, and is particularly useful in pulling nails from unfinished lumber.

In carrying out the invention, I provide a construction which includes an elongated lever shaped to provide a handle. A head at one end of the lever is of right-angled formation, one leg of the head being rigidly secured to the lever to provide a fulcrum about which the lever may be rocked during extraction of the nail. The other leg of the head is spaced closely from the adjacent end of the handle. A wedging plate is mounted to slide within the space between said other leg and lever and has a pair of claw members engageable under the head of the nail to be pulled. The sliding of the plate is for the purpose of permitting it to be driven into position adjacent the nail. After being properly positioned, the claw members are adapted to be cammed toward one another by adjacent portions of the head to grip the nail, after which the entire device is rocked bodily to pull the nail.

The main object of the invention, as noted above, is to provide a generally improved nail puller that will permit the speedy and easy extraction of nails in circumstances in which a claw hammer or the like is inadequate.

More specific objects of the invention are to provide a nail puller that will be capable of being manufactured at relatively low cost; will be rugged; and simple and compact in design.

Other objects will appear from the following description, the claim appended thereto, and from the annexed drawing, in which like reference characters designate like parts throughout the several views, and wherein:

Figure 1 is a side elevational view of a nail puller formed in accordance with the invention, a portion of the handle being broken away;

Figure 2 is a bottom plan view, the device being shown on a smaller scale;

Figure 3 is an end elevation, taken from the left of Figure 1;

Figure 4 is a longitudinal sectional view of the head end of the tool, taken on line 4—4 of Figure 2; and

Figure 5 is a perspective view of the tool as it appears when in use.

Referring to the drawings in detail, I provide an elongated, tubular lever 10 adapted to be gripped as a handle and having for this purpose, at its outer end, a hand grip 11. The inner end portion of the lever 10 is flattened as at 12, and is formed with a flat end surface 14 on

2

either side of which lugs 16 are secured rigidly to the flattened lever portion 10, said lugs extending outwardly from the portion 12 and having flat faces flush with the flat end surface 14 to provide lateral extensions of the same.

Rigid with the underside of the flat end portion 12 is a depending, oblong projection 18 received in an opening 20 of a head designated generally by the reference numeral 22. The projection is welded or otherwise fixedly secured within said opening, so as to rigidly connect the head and lever.

The head 22 is composed of a pair of integrally or otherwise rigidly joined plate-like legs 24, 26, disposed at right angles to each other. The leg 24, shown in bottom plan in Figure 2, extends in parallelism with the longitudinal center line of the lever 10, and provides, along its forwardly disposed or outer edge (seen as the left hand edge thereof in Figure 2) a fulcrum about which the device is rocked during extraction of nails.

The leg 26 is disposed transversely of the lever 10, in closely spaced, parallel relation to the flat end surface 14. To reduce cutting of the wood to a minimum, the several edges of said leg 26 are preferably beveled as at 28, and the outer face of the leg 26 has a sloped part 30, to facilitate rocking of the device during the later stages of the rocking movement thereof. The back face 32 of the leg 26 is wholly flat and lies in a plane parallel to that of the flat end surface 14.

Formed in the leg 24 is a slot 34, closed at its opposite ends and extending transversely of the lever, in registry with the space between leg 26 and end surface 14. A wedging plate, designated generally at 36, is loosely slideable within the slot 34, and has a flat, wide body 38 extending within and substantially filling the space between the flat surfaces 14, 32.

In the body 38 I provide a large, circular opening 40, with which communicates one end of an elongated slot 42 extending longitudinally and centrally of the body and opening at one end thereof, to define a pair of elongated, parallel claw members 44. The claw members 44 have sharpened or beveled inner longitudinal edges 46, and at their free ends are formed with tapered, nail-head-engaging claws 48.

The outer longitudinal edges of the claw members are curved to provide cam surfaces 50 engageable by the respective ends of the closed slot 34.

In use, the device is first positioned with its claws 48 arranged adjacent a nail N to be pulled. A hammer or similar tool, not shown, is then applied to that end edge of the wedging plate 36 that is remote from the claws 48, to drive the claws into position under the head of the nail.

As a next step, the hammer is struck lightly against that longitudinal edge of the flattened lever portion 12 that is remote from the projection 18, and this will cause the edges of the closed slot 34 to shift into camming engagement with the curved outer longitudinal edges of the claw members 44. As a result, the claw members will be cammed inwardly toward each other, into gripping engagement with the shank of the deeply embedded nail. This causes a tight grip to be obtained upon the nail.

The lever 10 is then gripped, and rocked counterclockwise in Figure 5, thus to cause joint rocking movement of the lever, head, and wedging plate. In this way, the nail is extracted from the surface in which it is embedded.

It is believed that the important functional characteristics and advantages of the device will be apparent from the description hereinbefore provided. However, it is thought worthy of special note that in addition to those advantages that are self-evident, the construction is particularly adapted for pulling nails from boards even after the head of the nail has been destroyed.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claim.

What is claimed is:

In a tool for pulling nails and like objects, a lever having on one end a flat surface, a head having a portion extending longitudinally along and secured to the side of said lever with a part projecting beyond and spaced from the flattened end surface of said lever and having another portion projecting at a right angle from the free end of said part, there being a closed slot in said part extending transversely of said lever, a flat wedge-shaped plate disposed between said another head portion and the flattened end surface of said head and removably and slidably mounted in said slot to shift transversely of the

handle into a position in which said plate is wedged within the slot and thus made rigid with the handle and head, said plate being formed integrally with side by side claw members resiliently connected to one another at one of their ends, for movement of the other ends of said claw members toward and away from each other, said claw members having outer side edges disposed obliquely to the line of movement of the plate, said outer side edges being engageable by opposite end portions of said slot on movement of the plate to the wedged position thereof, whereby to bias the claw members toward one another into gripping engagement with a nail to be pulled.
